SPLIT HEATING SYSTEM

Thomas Charles Gower, Greenville, S. C.

Application August 25, 1939, Serial No. 291,968

5 Claims. (Cl. 237—9)

This invention relates to improvements in heating systems especially of the kind known as a split heating system. This system combines the elements of direct and indirect transfer of heat, and its underlying virtue lies in the fact that full advantage is taken of the fuel, those portions of the products of combustion which do escape having been depleted of their heating efficacy to the lowest possible degree. The nature of the improvements is better understood by referring to the following objects of the invention:

First, to provide a heating system of the so-called split type because of its taking advantage of both the direct and indirect transfer of heat, differing from known split systems by reason of its simplification.

Second, to provide a split heating system which is structurally arranged so as to be both efficient and fast in operation.

Third, to provide a split system wherein one of the most important features resides in the heat control, the principle of which is the thermostatic regulation of hot water circulation for a preheater, the latter being situated in the path of the returning cool air so as to preheat it preliminarily to its contacting the hot furnace jacket.

Fourth, to provide a split system embodying both hot water (or steam) radiators and hot air registers in various portions of the house, the thermostatic control being such that the heating effect at both of these devices is kept substantially uniform so as to avoid undue variation in the room temperatures, as produced by a radiator and by a register.

Fifth, to provide an improvement in the humidifier which is more efficient than current devices of this kind inasmuch as it is embodied in the firedoor frame, hence is located fairly high in the air stream.

Other objects and advantages will appear in the following specification, reference being had to the accompanying drawings, in which:

Figure 1 is a central vertical section of the furnace and some of its immediately associated auxiliaries.

Figure 2 is a central vertical section taken on the line 2—2 of Fig. 1.

Figure 3 is a horizontal section taken on the line 3—3 of Fig. 2, the view being turned 90° as to position so as to match Fig. 1.

Figure 4 is a diagram of the electrical controls.

Figure 5 is a detail vertical section taken substantially on the line 5—5 of Fig. 2, and illustrating a built-in heater.

Figure 6 is a section taken on the line 6—6 of Fig. 1 illustrating an improved humidifier.

Figure 7 is a detail sectional view of one of the stay-bolts.

Figure 8 is a detail sectional view of a portion of the preheating coil.

One of the several advantages of the instant heating system is that it can be used solely for warm air distribution in a closed air circuit, or can be used for the partial supply of warm air and the supply of either hot water or steam to a radiator system. The latter arrangement is depicted in the drawings, thus representing a true split system, but it is readily understood that the apparatus can be devoted solely to the delivery of warm air, in which respect the invention embodies a feature of particular importance.

Reference is made to the drawings. The so-called closed-air circuit comprises the heating apparatus itself (Figs. 1, 2 and 3), the branches of which lead to and from the rooms above and finally the rooms themselves. The heating apparatus is generally designated 1. The hot air delivery branch is designated 2 (Fig. 2) and the cool air return branch is designated 3. The branch 2 is attached at 4 in any suitable way over and around a large opening 5 in the roof 6 of a casing 7. This casing comprises the complete enclosure of a furnace, the details of which are now described.

Said furnace is designated 8. It comprises a flueless compartment which in the instance of the use of the oil burner 9 (Fig. 1) has the customary ash-pit lined with firebrick as at 10. The furnace has a fire door frame 11 and a gas outlet 12.

A water jacket 13 surrounds most of the furnace 8. The walls of the furnace and water jacket are offset relatively to each other, both inwardly and outwardly as seen in Figs. 1 and 2, in approximate line with the top of the firebrick lining 10. The jacket 13 contains a volume of water 14, and obviously so, this being supplied and kept at the desired level by any of the means currently known for the purpose.

The furnace and water jacket 13 are held in spaced relationship by a suitable number of stay-bolts 15. These are made in accordance with 50 the showing in Fig. 7. Here the stay-bolt 15 is indicated as being threaded its full length as at 16. The stay-bolt is screwed into matching holes in the furnace and water jacket walls. The threads alone tend to prevent separation of 55 said walls under internal pressure, but in order

to insure that purpose the ends of the stay-bolt are riveted over at 17. The riveting also is a contribution toward a watertight joint.

A radiator chamber 18 (Figs. 1 and 3) has direct communication with the interior of the furnace 8 by means of the gas outlet 12. The outlet extends through and beyond the water jacket 13 and holds the radiator chamber 18 in spaced relationship at 19 to the rear wall of the jacket 13. The radiator chamber 18 preferably comprises two compartments 18^a which are coupled near the bottom by a duct 18^b and at a point substantially in line with the gas outlet 12 by a passageway 18^c. This passageway contains the pivoted damper 18^d which is adapted to be turned in any desired way, for example, by handle 18^e (Fig. 3), proper attention being paid to making gas-tight joints at the points of mounting of the chamber pivot in the walls of the passageway 18^c. The radiator chamber 18 receives all of the products of combustion from the furnace. The air surrounding both the jacket 13 and each of the compartments 18^a is thus heated from two heat sources, first indirectly from the furnace 8 by way of the water volume 14, second directly by virtue of contact with the extremely hot chamber 18.

In order to make the radiator compartments more effective for the purpose, its walls are slightly tapered at 20 (Fig. 3) in the lateral directions. The spaces 19 thus become progressively wider toward the lateral margins of the radiator chamber, providing for the ample access of the circulating air to the radiator chamber. This formation comprises a circuitous course for the products of combustion in their flow toward the chimney flue 21.

Another particular purpose of the invention is to make sure that all of the cool air entering the casing 7 by way of the return branch 3 is brought into direct contact with the jacket 13 and the radiator chamber 18. A strong-updraft is secured in these confined quarters by a horizontal baffle 23 (Fig. 3) which follows the inside contour of the casing 7 and is cut out at 24 closely to the jacket and radiator so as to define a restricted passage. This horizontal baffle is generally in the nature of a shelf, and it is approximately on a level with the furnace and water jacket offsets and the top of the firebrick lining 10. The latter also becomes very hot because of the discharge of the flame from the oil burner 9 into the chamber on the inside, consequently the returning cool air which, incidentally by this time has become preheated, starts at once to derive the heating benefit of the furnace.

In other words, the returning air is so controlled that the highest possible amount of heat is imparted to it by virtue of compelling the air stream to strike the hottest parts of the heating apparatus and to remain in contact therewith until the moment of discharge from the casing 7 into the branch 2. In furtherance of the last named purpose, the branch 3 is attached at 25 to a receiver 26. This receiver comprises a compartment at one side of the casing 7, there being communication between the two by way of an opening 27 (Fig. 2).

This opening constitutes the outlet of a blower casing 28 within the receiver 26. A fan 29 is revolvable in the casing, being driven by an electric motor 30, and air is drawn into the casing 28 by the operation of the fan 29 through an opening 31. The blower casing 28 actually pro-

vides the channel of communication between the receiver 26 and the furnace casing 7.

The receiver 26 is partitioned at 32 (Fig. 2). Said partition underlies the branch 3, and it is desirably dished although the dishing is not imperative. Said partition defines a constricted air opening 33. This opening has a preheating coil 34 fitted in it like a grille (Fig. 3). Said coil intercepts all of the air returning in the branch 3 and its purpose is to preheat said air and thus warm the latter preliminarily to its being introduced into the casing 7.

Said preheating coil 34 is piped at 35, 36, to the water jacket 13. It comprises an extension 15 of the water jacket which reaches out in a manner of speaking, to a place where contact of the cool returning air can be made with it, prior to the cool air stream re-entering the furnace casing 7 which is the fundamental source of heat therefor. Hot water from the jacket 13 is periodically circulated through the coil 34 by a pump 37 (Fig. 2) which is adapted to be driven by an electric motor 38.

Reverting to the preheating coil 34, brief mention is desired to be made of its structural details. A pair of heaters 39 (Fig. 3) is connected by a plurality of tubes 40 (Fig. 8). These tubes are spaced apart to provide air passages, and they are equipped with fins 41 which augment the radiation of the heat from the water contained by the tubes.

Before describing the control diagram in Fig. 4, reference is desired to be made to collateral features of the invention. One of these has to do with the fire door-frame 11 (Fig. 1). This frame is utilized as the basis of an improved humidifier 42. The latter comprises one long pan 43 which is adapted to hold a quantity of water 44 that is supplied by way of a valve 45 (Fig. 3) from a pipe 46. A valve 45 is controlled by the float 41 and when the level of the water drops to a predetermined extent the valve 45 opens automatically to replenish the supply.

The advantage of this arrangement in the humidifier 42 is that a positive evaporation of the water is insured. The pan 43 and its contained volume of water represents a fair amount of weight. Since the frame 11 is made of cast iron it is adequately strong to support the humidifier. The pan is firmly held in place by flanges 48 which stand up from the frame 11. These flanges, and others like them at the bottom of the frame, are intended to enable the affixation of the frame to the jacket and casing walls. They also serve the purpose of retaining the water pan.

A secondary purpose of the heating apparatus is to furnish a supply of hot water in the summertime. To that end a heater 49 (Figs. 2 and 5) is built into the jacket 13 as shown. It comprises headers 50 which are emplaced upon the outside of the water jacket. The distance between these headers is spanned by a plurality of water tubes which are immersed in the water 14 inside of the jacket. The headers 50 are piped at 51 to a storage tank 52. The latter receives its supply from the service pipe 53 and when one of the fixtures in the house is opened, the pressure of water from the cold side drives the previously heated water up a pipe 54 which leads to the fixture.

Inasmuch as the built-in heater 49 is intended to supply hot water in the summer as well as winter, provision is made for diverting the heated air from the delivery branch 2. This provision

comprises twin dampers 49a, 50a, which are connected by a link 51a of a suitable type. They are hinged contiguously to the opening 5, and a lateral opening 52a in the casing 7 (Fig. 2) and when one of the dampers, for example the damper 49a, is moved to the closed position by the lever 53a, the damper 50a is moved correspondingly to uncover the lateral opening 52a and let the heat out into the basement.

Reference is now made to the diagram in Fig. 4 which illustrates the electrical control of the system. The wires 55, 56, which lead to and from a source of current, have branches 57, 58, 59, 60 and 61 which embrace in the order stated a warm air thermostat 62, the blower and hot water circulator motors 30 and 38 as well as a stoker or oil burner motor 63, a thermal control 64, an immersion control 65 connected in parallel with the room thermostat 66, and a limit control 67 which is a pressure control connected in series with the firing device.

These control devices are all of a known character and for that reason their details are omitted from the diagram. The thermostat 62 is emplaced in the midst of the house space adapted to be heated by the warm air. The thermostat 66 is adapted to be emplaced in that part of the house which is intended to be heated by radiators. It maintains the necessary temperature in the water 14 to operate the indirect hot water heater for the domestic hot water supply. Reference is made to Fig. 1 wherein a radiator 68 is shown piped at 69, 70, to the top and bottom of the jacket 13. The steam is adapted to circulate through the radiator 68 so that the room heating effect can be produced indirectly through the radiator and directly through the expelled warmed air.

The operation

The operation is readily understood. It is assumed first that the rooms of the house which are a part of the closed air circuit, are intended to be heated only by warm air. The thermostat 62 is usually set for a room temperature of 72°. When the temperature drops below that amount the thermostat switch closes an electrical circuit through the motor 38 which starts the circulation of hot water 14 from the jacket 13 through the preheating coil 34. The immersion control 65 which comprises an immersion aquastat operates the burner motor 63 to maintain the water at a predetermined temperature. When the thermostat 62 is closed the result is the starting of the hot water circulator 38 whereupon water is pumped through the preheating coil 34. This reduces the temperature of the water and causes the firing device (motor 63) to operate.

This coil is intended to be kept quite hot usually from 150° to 180°. When the temperature rises in the coil 34 into the foregoing range, the blower motor 30 is started by means of the thermal control 64. Said control is in contact with the coil 34. The room thermostat 66 operates the firing device to produce the necessary steam pressure to heat the radiator 68. Either thermostat 62 or 66 can start the flow of heat independently for the areas which they control.

With respect to the immersion control 65 and limit control 67 it will be noted that the latter is in series with the line in which the oil burner motor 63 is connected. Its purpose is to limit and control the steam pressure. The immersion aquastat 65 is connected in parallel with the thermostat 66.

Assuming that the aquastat 65 is set at 190

degrees it will maintain the water at this temperature, which, obviously is below the 212 degree boiling or steam point. When the area controlled by the thermostat 66 calls for heat the firing device 63 will be operated until the circuit is opened at the thermostat 66, or until the pressure control 65 opens the circuit. No heat will be conveyed to the warm air area controlled by the thermostat 62, unless said thermostat closes.

In the winter operation of the heating system the damper 18d (Fig. 1) is intended to be closed. This prevents the products of combustion from flowing through the passageway 18c directly to the chimney flue 21. The hot gases are diverted downwardly, passing from one compartment 18a to the other by way of the duct 18b. A high percentage of the heat value of the gases is thus utilized, the result being an extremely hot radiator 18 which, in turn is certain to heat the circulating air to a high degree.

For summer operation it is undesirable to have this effect, and for that reason the damper 18d is opened so as to by-pass the hot gases directly to the chimney flue. The primary purpose of summer operation of the heating system is to heat the water in the heater 49 (Fig. 2) for domestic uses.

I claim:

1. A split heating system comprising a closed air circuit including air delivery and return branches, a power fan to induce a uni-directional air flow in said circuit, a furnace having a water jacket, a space-heating radiator piped to the water jacket and adapted to warm the air of a room in which it is located, a radiator chamber connected to the furnace for receiving the escaping products of combustion, a casing enclosing the furnace with its jacket and radiator chamber to confine the heat radiating therefrom and being coupled in said system to pre-heat the air entering the delivery branch thus to augment the heating function of said space-heating radiator, and a preheating coil situated in the return branch to intercept and preheat the spent and confluent air prior to its reentrance into the casing, said coil being piped to the jacket to utilize some of the hot water for the preheating.
2. A split heating system comprising a closed air circuit including air delivery and return branches, the return branch having an opening, a furnace having a water jacket, a radiator chamber connected to the furnace for receiving the escaping products of combustion, a casing enclosing the furnace with its jacket and radiator chamber to confine the radiant heat and being coupled in said system to supply the heat for the air passing into the delivery branch, a preheating coil occupying said opening like a grille, intercepting the air in the return branch and preheating it prior to its reentrance into the casing, said coil being piped to the jacket, a circulating pump coupled in said piping, and a motor to drive the pump, having a thermal control in substantial contact with the preheating coil.
3. In a heating system, a casing for the supply and return of hot and cool air, a furnace located in the casing, spaced in from the walls thereof to define a surrounding air space, a firedoor frame extending from the furnace across the space to the outside of the casing, and a humidifier supported upon and thereby utilizing said frame as a mount for the humidifier in said space.
4. In a heating system, a casing for the supply and return of hot and cool air, a furnace located

in the casing, spaced in from the walls thereof to define a surrounding air space and having a hot gas outlet, a radiator located in said air space, consisting of compartments coupled at one end, one of the compartments being connected to said gas outlet adjacent to the other end of the radiator, said compartments having a communicating passageway and a chimney flue connection substantially in line with said outlet, and a damper situated in said passageway, being adjustable to either of two positions respectively to close said passageway and by-pass the gases into the compartments and through the coupling or to open said passageway for the escape of the gases directly to the chimney flue.

5. In a heating system, a casing having a hot

air delivery branch leading to a room from an opening in the top, a furnace located in the casing, and adapted to be fired to supply heat to said branch, said casing having a lateral opening, 5 a water heater situated in close proximity to the furnace to derive heat therefrom, a storage tank to which the heater is piped, and twin dampers hinged contiguously to the respective top and lateral openings and being connected with a link, the operation of said dampers including opening the lateral damper and simultaneous closure of the top damper to confine the heating effect to the water heater and keep the heat from entering the delivery branch to heat the room.

15

THOMAS CHARLES GOWER.
